Patented June 11, 1912.

UNITED STATES PATENT OFFICE.

EARL R. SNEDAKER, OF PHILADELPHIA, PENNSYLVANIA.

PUZZLE.

1,029,240.

Specification of Letters Patent. Patented June 11, 1912.

Application filed September 28, 1911. Serial No. 651,672.

To all whom it may concern:

Be it known that I, EARL R. SNEDAKER, a citizen of the United States, residing at Philadelphia, in the county of Philadelphia and State of Pennsylvania, have invented 5 certain new and useful Improvements in Puzzles, of which the following is a specification.

My invention relates to improvements in 10 puzzles, and more particularly to a puzzle or game apparatus which requires nerve and skill in its manipulation to accomplish the result.

A further object is to provide a device of 15 this character with a plurality of partitions having slots and openings through which a bar is positioned, and a ball is provided which is adapted to be supported on the bar and manipulated thereby through the several 20 openings in the partitions without falling from the bar, said openings being out of alinement making the operation a difficult one.

With these and other objects in view, the 25 invention consists in certain novel features of construction and combinations and arrangements of parts as will be more fully hereinafter described and pointed out in the claims.

30 In the accompanying drawings: Figure 1, is a perspective view illustrating my improvements. Fig. 2, is a fragmentary view in cross section through the rear end of the device, and Fig. 3, is a view in longitudinal section through the center of the device.

35 1, represents a base which is preferably rectangular and provided around its edges with walls or flanges 2. Throughout the length of the base, a plurality of vertical partitions 3 are secured, and spaced apart. While I have shown five of such partitions, I would have it understood that I may change the number at will. Between the rearmost partition 3, and the rear end of 40 the base, a block 4 is located, and has its upper face inclined to its center where a groove 5 is provided. All of the partitions 3 are provided centrally with vertical slots 6 which aline with the groove 5, and are 45 adapted to receive a bar 7 which projects through the notched end 8 of the end wall 2, and is provided with a handle 9. This bar 7 has its upper edge curved transversely in conformity to the curvature of a ball 10, 50 and block 4 is recessed as shown at 11 to guide the ball in position onto the edge of

bar 7. The several partitions are provided with openings 12 communicating with the slots 6, and of a size just sufficient to allow the ball 10 to pass therethrough. It is to 60 be understood that each partition has but a single opening 12, and that the openings in the several partitions are out of alinement so that the bar 7 must be nicely manipulated up and down to convey the ball through the 65 several openings without knocking the ball off the bar. The game is therefore one of skill requiring a steady nerve, because the slightest movement will drop the ball off the bar. To render the game more interesting, I have marked the several partitions in 70 order as follows: "Field", "First base", "Second base", "Third base", and "Home". The game therefore represents a baseball 75 game, so that theoretically the ball passes first through the field and then the runner reaches first base, second base, third base, and home. If he reaches home, the puzzle has been accomplished.

In constructing the device, I preferably 80 use wood for the several parts with the exception of the ball which I preferably make of composition, but I would have it understood that the particular materials are not essential, because they may be varied to suit 85 conditions.

Various slight changes might be made in the general form and arrangement of parts described without departing from my invention, and hence I do not limit myself to 90 the precise details set forth, but consider myself at liberty to make such changes and alterations as fairly fall within the spirit and scope of the appended claims.

Having thus described my invention, what 95 I claim as new and desire to secure by Letters Patent is:

1. A device of the character described, comprising a base, a vertical partition on said base having a slot therein, and an opening in said slotted portion, a bar positioned through the slot, and a ball adapted to be supported on the bar and manipulated through the opening, substantially as described. 100

2. A device of the character described, comprising a base, a plurality of vertical partitions on the base, said partitions having alined slots, openings in said partitions in the slotted portions thereof, said openings being out of alinement, a bar positioned through said slots, and a ball adapted to be 110

supported on said bar and manipulated thereby to pass the ball through the said openings in the partitions, substantially as described.

- 5 3. A device of the character described, comprising a base, a vertical partition on said base having a slot therein, and an opening in said slotted portion, a bar positioned through the slot, a ball adapted to be supported on the bar and manipulated through the opening, said bar having its upper edge curved concentrically with the curvature of the ball, and a handle on the outer end of said bar, substantially as described.
- 10 15 4. A device of the character described, comprising a base, a plurality of vertical partitions on the base, said partitions having aligned slots, openings in said partitions in the slotted portions thereof, said openings being out of alignment, a bar positioned through said slots, and a ball adapted to be supported on said bar and manipulated thereby to pass the ball through the said openings in the partitions, said bar having its upper edge curved concentrically with the curvature of the ball, and a handle on the outer end of said bar, substantially as described.
- 20 25 30 5. A device of the character described, comprising a base, a wall around said base,

a plurality of vertical partitions on said base, said partitions all having registering longitudinal slots therein, openings in said partitions in the slotted portions thereof, said openings being out of alignment, a bar projecting through all of said slots, a ball, and an inclined block at the inner end of said base constructed to guide the ball onto the bar, substantially as described.

6. A device of the character described, comprising a base, a wall around said base, a plurality of vertical partitions on said base, said partitions all having registering longitudinal slots therein, openings in said partitions in the slotted portions thereof, said openings being out of alignment, a bar projecting through all of said slots, a ball, a block secured to the rear end of said base, a central groove in said block receiving said bar, and curved recesses at opposite sides of said groove supporting the ball in position on the bar, substantially as described.

In testimony whereof I have signed my name to this specification in the presence of two subscribing witnesses.

EARL R. SNEDAKER.
